UNITED STATES PATENT OFFICE.

HENRY PENNINGTON, OF PHILADELPHIA, PENNSYLVANIA.

DESIGN FOR AN ADVERTISING-LABEL.

SPECIFICATION forming part of Design No. 13,294, dated September 12, 1882.

Application filed August 21, 1882. Term of patent 7 years.

To all whom it may concern:

Be it known that I, HENRY PENNINGTON, a citizen of the United States, residing at the city of Philadelphia, in the county of Philadelphia and State of Pennsylvania, have invented and produced a new and original Design for Advertising-Labels, of which the following is a specification, reference being had to the accompanying drawing or illustration, forming part hereof.

The said drawing or illustration is described substantially as follows: On a parallelogram placed cornerwise is a landscape with trees, in the foreground of which is a representation of a 15 woman bearing in her hands a wide-mouthed jar. To the right of the same is a circular figure with a shaded rim and ground. To the right of said circular figure is a convolute figure, as though the end of said horizontal band were curled up.

20 These appear as if laid upon a horizontal band. Above said parallelogram, and also above said circular figure, and extending to the right and left, is an olive branch laden with fruit and leaves, and showing some blossoms. All said

25 things have behind them representations of a plaited or braided fabric placed diagonally and folded over so as to hang perpendicularly, all which will more fully appear by reference to the said illustration, which is itself inclosed by straight lines.

It will readily be understood by those who use this design in an article of manufacture that all the parts thereof may be printed or worked in appropriate colors, so as to more clearly depict the fruit and other things represented, 35 and also that the parts herein shown in blank may be more or less filled in with any advertising matter or wording, although of course such matter or wording does not form any part of the said design.

30 I claim—

The design for an advertising-label, consisting of the representation of a parallelogram containing a landscape with the figure of a woman in the foreground, the light-rimmed circular figure, the olive branch, fruit, leaves, and blossoms, and other parts, all substantially as hereinbefore described.
